UNITED STATES PATENT OFFICE.

MAURICE MATHY, OF FLÉMALLE GRANDE, BELGIUM.

APPARATUS FOR FINISHING THE MOUTHS OF GLASS BOTTLES.

1,188,669.

Specification of Letters Patent. Patented June 27, 1916.

Application filed May 18, 1915. Serial No. 28,954.

To all whom it may concern:

Be it known that I, MAURICE MATHY, a subject of the King of Belgium, residing at 28 rue Léopold, Flémalle Grande, Belgium, 5 have invented certain new and useful Improvements in Apparatus for Finishing the Mouths of Glass Bottles; and I do hereby declare the following to be a full, clear, and exact description of the invention, such as 10 will enable others skilled in the art to which it appertains to make and use the same, reference being had to the accompanying drawings, and to letters or figures of reference marked therein, which form 15 a part of this specification.

The present invention has for its object a finishing machine for the mouths of glass bottles, or other similar glass vessels, especially intended for rendering as regular as 20 possible the position and the shape of the mouths before the bottles are removed from the mold in which they are blown.

The proper action of this machine is to dispose the material of the bottle neck in 25 equal thickness against the wall of the mold, to give to the mouth its definitive dimensions, a regular conical shape and a finish sufficient for the stoppering with a cork.

By means of this improved machine, it is 30 possible to obtain these results without excessive expenses for wages or mechanical power.

Another advantage of this machine is that all the bottles of a same set are made 35 quite similar.

These results are obtained by using a conical rotary tool supported by a frame in such a manner that it can be moved and arranged without groping in the right position 40 in a line with the axis of a bottle mouth and then moved parallelly to said axis so as to be brought into contact with the material of the bottle neck. This parallel motion is also suitably limited according to 45 the dimensions to be given to the mouth. When the tool is removed from its position in a line with the axis of the mouth, it is carried away without groping onto a flame, the function of which is to heat the 50 tool and at the same time to cover it with lamp-black.

It has also been found advantageous to provide the conical tool with grooves arranged along generating-lines of the cone; 55 the work done with a grooved tool is more

perfect because the grooves allow the air contained in the bottle to escape.

The drawings show by way of example a preferred embodiment of the invention.

Figure 1 is a side view of the machine. 60 Fig. 2 is a partial view from behind.

The conical tool 1 is secured by any suitable means to the vertical rotary shaft 2 journaled in bearings 3 and 4 of a frame 5 and driven by means of a flexible shaft 6. 65 The vertical shaft 2 is also adapted to slide longitudinally in the bearings 3 and 4, but it is prevented from sliding down by a lever 7 turning upon a pivot 8 of the frame; the arm 7 of said lever, which terminates 70 in a handle, surrounds a collar 9 adapted to turn without sliding upon the shaft 2 and provided with two pins 10 which pass through slots 11 in the lever 7. The other arm of said lever is provided with a counterweight 36, the position of which on the lever can be altered in order to balance the 75 weights of shaft 3, shaft 6 and fittings. When sliding upward in its bearings, the vertical shaft 2 is stopped by the bearing 3 80 and in the other direction by a piece of flat-iron 12 bent at right angle, the horizontal part of which is provided with a hole through which the shaft passes. In the vertical part a vertical slot is provided 85 through which passes a screw-threaded pin 13 secured to the bearing 4. The piece 12 can by this way be secured at any desired height by means of a nut 14. India-rubber or other elastic buffers 15 are arranged on 90 both sides of the collar 9.

The frame 5 is provided with a sleeve 16 adapted to slide and to rotate on the vertical post 17 supported by the base-plate 18; this sleeve rests by the interposition of 95 ball-bearings on a collar 19 that can be secured at any required height on the post 17 by means of a screw 20 terminating in a handle; the end of said screw is guided in a groove 21 of the post. The sleeve 16, 100 which revolves on the collar 19, can be secured to the same in four distinct positions. Therefore, the collar is provided with four bolting-notches such as 22 and 22' arranged at 90° one from the other on the periphery of the collar. Sliding in a longitudinal groove of the sleeve 16 is mounted a bolt 23 provided with a pivot 24 passing through the slot 25 of a lever 26. Said lever is secured to a shaft 27 journaled in 110

- bearings 28 of the frame and terminating in a handle 29. By lifting said handle 29, it is possible to lift the bolt 23 out of the bolting-notch, so that the sleeve 16 and the frame 5 is allowed to turn freely. The bolt 23 is inclined to fall automatically into the notches of collar 19 by the weight 30; it is pressed in the groove of the sleeve 16 by a spring 31.
- 10 In the base-plate 18 is a hollow 32 adapted to contain the bottom of the mold 33 in such a manner that the axis of the mold is in a line with the axis of the tool 1 when the bolt 23 has been forced into the notch 22. Upon the base-plate 18 is also secured an oil lamp 34 or a Bunsen burner with lighting-flame. Said lamp is arranged in such a position that the tool 1 is carried exactly into the flame when the frame is turned and the bolt 23 forced into the notch 22'. The function of this flame is to heat the tool 1 and to cover it with lamp-black during the time that the frame is turned so as to clear the access to the mold. The apparatus being in this last described position, with the tool 1 in the flame, the glass is introduced in the mold 33 and blown into a bottle; but it must be noted that after this operation the mouth of the bottle is always rather irregular. By operating the handle 29, the workman renders the frame free and turns the same, bringing the tool 1 over the mouth. When the exact position of the tool 1 is attained, the bolt 23 falls into the notch 22 and locks the frame 5; the workman then moves the handle 7 down and the rotary tool 1 is driven into the mouth of the neck for finishing the same.
- 40 It is to be noted that owing to the conical shape of the tool, it is possible to vary the final inner diameter of the mouth by varying the position of the adjustable flat-iron 12 against which the lower buffer 15 strikes.
- 45 Breaking of the bottle neck, or sticking of the tool to the hot glass must never be feared because the tool has been previously heated and covered with lamp-black. On the other hand the tool is provided with 50 grooves arranged along generating-lines of the cone. These grooves are numerous and without sharp edges, so that they do not scrape out glass from the mouth.
- What I claim is:
- 55 1. In an apparatus for finishing the mouths of glass bottles, the combination of an angularly displaceable frame, bearings in said frame, a rotary conical tool journaled in said bearings, a mold and means to
- 60 produce a heating and carbonizing flame disposed beneath said frame on a circle concentric with the axis of rotation of the angularly displaceable frame, and means for controlling the location of the angularly displaceable frame, so that the rotary coni-

cal tool is arranged in alinement with the mouth of the mold or in contact with the heating and carbonizing flame.

2. In an apparatus for finishing the mouths of glass bottles, the combination of an angularly displaceable frame, bearings in said frame, a rotary conical tool having grooves arranged along the generating lines of the cone and journaled in said bearings, a mold, and means to produce heating and carbonizing flame disposed beneath said frame on a circle concentric with the axis of rotation of the angularly displaceable frame, and means for controlling the location of the angularly displaceable frame so that the rotary conical tool is arranged in alinement with the mouth of the mold or in contact with the heating and carbonizing flame.

3. In an apparatus for finishing the mouths of glass bottles, the combination of an angularly displaceable frame, bearings in said frame, a rotary conical tool having grooves arranged along the generating lines of the cone and journaled in said bearings, means for longitudinally displacing said tool with respect to the bearings, a mold and means to produce heating and carbonizing flame disposed beneath said frame on a circle concentric with the axis of rotation of the angularly displaceable frame; and means for controlling the location of the angularly displaceable frame so that the rotary conical tool is arranged in alinement with the mouth of the mold or in contact with the heating and carbonizing flame.

4. In an apparatus for finishing the mouths of glass bottles, the combination of an angularly displaceable frame, bearings on said frame, a rotary conical tool having grooves arranged along the generating lines of the cone and journaled in said bearings, means for longitudinally displacing said tool with respect to the bearings, a collar and coacting stops for limiting the longitudinal displacement of the tool, a mold and means to produce a heating and carbonizing flame disposed beneath said frame on a circle concentric with the axis of rotation of the angularly displaceable frame, and means for controlling the location of the angularly displaceable frame so that the rotary conical tool is arranged in alinement with the mouth of the mold or in contact with the heating and carbonizing flame.

5. In an apparatus for finishing the mouths of glass bottles, the combination of an angularly displaceable frame, means for vertically adjusting said frame, bearings on said frame, a rotary conical tool having grooves arranged along the generating lines of the cone and journaled in said bearings, means for longitudinally displacing said tool with respect to the bearings, a collar and coacting stops for limiting the longi-

tudinal displacement of the tool, a mold and means to produce a heating and carbonizing flame disposed beneath said frame on a circle concentric with the axis of rotation of the angularly displaceable frame, and means for controlling the location of the angularly displaceable frame so that the rotary conical tool is arranged in alinement with the mouth of the mold or in contact with the heating and carbonizing flame.

6. In apparatus for finishing the mouths of glass bottles, the combination of an angularly displaceable frame, a vertical post for supporting said frame, means for adjusting the position of the frame along said post, bearings on said frame, a rotary conical tool having grooves arranged along the generating lines of the cone and journaled

in said bearings, means for longitudinally displacing said tool with respect to the bearings, a mold and means to produce a heating and carbonizing flame disposed beneath said frame on a circle concentric with the axis of rotation of the angularly displaceable frame, and blocking means for controlling the location of the angularly displaceable frame so that the rotary conical tool is arranged in alinement with the mouth of the mold or in contact with the heating and carbonizing flame.

In testimony whereof I affix my signature in presence of two witnesses.

MAURICE MATHY.
